HERMANN CHRISTIAN WILHELM WEYHE, DECEASED,

BY

Alfred P. Elten
ADMINISTRATOR, ATTORNEY.

UNITED STATES PATENT OFFICE.

ALFRED P. ELTEN, OF CLEVELAND, OHIO, ADMINISTRATOR OF HERMANN CHRISTIAN WILHELM WEYHE, DECEASED, ASSIGNOR TO CARL B. T. WILCKENS, OF BREMEN, GERMANY.

FLOORING AND CEILING.

SPECIFICATION forming part of Letters Patent No. 639,544, dated December 19, 1899.

Application filed December 30, 1897. Serial No. 664,680. (No model.)

To all whom it may concern:

Be it known that HERMANN CHRISTIAN WILHELM WEYHE, deceased, late a citizen and a resident of Bremen, in the Empire of Germany, did invent a new and useful Flooring and Ceiling, (patented in Germany May 8, 1895, No. 81,135, and September 4, 1895, No. 82,941,) of which the following is a full, true, and exact description.

10 This invention relates to floor and ceiling constructions of a fire-resisting nature; and the object of the improvement is to increase the load-bearing capacity of such floors in a simple and rational manner, and more particularly to obtain a floor and ceiling construction possessing a higher degree of elasticity than is found with other constructions of a similar nature in addition to satisfactory load-bearing propensities. This is accomplished by providing curved bars, in this specification named "arch-bars," in the floor-forming material, substantially as set forth in the following description, reference being had to the accompanying drawings, in which—

25 Figure 1 represents a transverse sectional view of a detached floor-span formed by metallic girders or beams and provided with an arch-bar of the kind above referred to. Fig. 2 illustrates the application of such bars in pairs. Fig. 3 shows still another application of said bars by alternating arch and inverted arch-bars. Figs. 4, 5, and 6, respectively, represent longitudinal sections of the different floor constructions shown in Figs. 1, 2, and 3.

35 Like letters of reference denote like parts in the drawings and specification.

Such arch-bars are formed of metal, preferably iron rods, flat bands, or similar pieces of any suitable cross-section, curved to a degree about as shown in the drawings. It is apparent that to a certain extent the more a bar of this description is curved the more weight the same can support. It is therefore advisable to curve such arch-bars to as great an extent as is practicable and as the thickness of the floor or ceiling will admit. These arch-bars are placed in the joints *a* of the floor and ceiling forming material *B*, single or in pairs, as shown in Figs. 1 and 2, 4 and 5, 40 should sectional material, as bricks, stones, or

similar blocks of mineral or any other fire-resistant matter, be employed, or one arch-bar *A* may be used to two or more inverted arch-bars *A'*, as shown in Figs. 3 and 6, or there may be more arch-bars and fewer inverted 55 arch-bars.

Where the floor and ceiling is formed of a mass applied in a plastic state the arch-bars of the required number and arranged for best effect are placed in position and the floor-forming material applied between the arch-bar, supporting-beams, girders, or walls, and about and around the arch-bars in such a manner as to completely cover and incase or envelop said arch-bars. 60

It is a well-known fact that upwardly-curved arch-bars are capable of offering a greater resistance to pressure from above than straight horizontal bars or rods—this especially when subjected to sudden violent strains, as would 65 be caused by heavy objects like safes, beams, &c., falling onto a floor in case of a fire. In such instances a fire-resisting floor construction possessing a maximum degree of elasticity 70 will be most desirable. To obtain, however, 75 the best possible results, it is essential that not only these arch-bars should be prevented from moving sidewise—that is, horizontally—in a direction at right angles to the arch-bar, but that they are also thoroughly united with the 80 floor-forming material. The first is effected by making the joints of the floor and ceiling forming material into which arch-bars are laid as narrow as practicable, while to secure intimate contact of all parts of the floor and 85 ceiling a mortar or cement of satisfactory adhesive qualities is applied between all parts.

When employing only upwardly-curved arch-bars in constructing floors according to this invention, there is a tendency of the arch-bars to lengthen to an extent depending on the load sustained by the floor, resulting in a lateral strain against the supporting beams or girders or equivalent, which strain need not necessarily be detrimental or to be avoided. Should, however, these floor-supports 90 not possess the requisite stability and strength to properly withstand all lateral strains to which they may be subjected, or should it be deemed inexpedient to subject the floor-sup- 95 100

porting beams or girders or equivalent to any lateral strains at all, then downwardly as well as upwardly curved bars combined are placed and embedded in the floor-forming material, 5 in the joints or otherwise, as above alluded to.

By combining in the construction of a floor downwardly and upwardly curved bars with the sectional or other floor-forming material, all parts in intimate contact and thoroughly 10 held together through the medium of a mortar or cement, the whole becomes a rigid plate or platform of superior load-bearing capacity and possessing a maximum degree of elasticity. Furthermore, all lateral strains will 15 practically be eliminated, since the forces appearing at the downwardly-curved bars not only act in a different direction as those appearing at the upwardly-curved bars, but neutralize or equalize the latter, in conse- 20 quence of which only strains in a downward direction are received by the floor-supports.

Referring to Figs. 1 and 4, arch-bars A are shown placed in the joints *a* of sectional material or blocks B, the bars reaching from one 25 girder across to the other. In Figs. 2 and 5 inverted arch-bars A' have been added to arch-bars A, one of each being placed in every joint *a*. In Figs. 3 and 6 each joint *a* receives only one bar, either an upwardly or a down- 30 wardly curved one. Ordinarily such a combination of arch-bars A and inverted arch-bars A' will afford greatest resistance to pressure or load for a given expenditure in iron. Inverted arch-bars A' can also be employed

without upwardly-curved arch-bars where it 35 should be desirable that the lower surface of floor extends somewhat below lower parts of supporting beams or girders to enable the covering up and protecting these girders against fire. In an arrangement of this description 40 the middle part of the inverted arch-bar A' being very near to the lower surface of the floor the latter is materially strengthened.

Having thus fully shown and described the invention, what is claimed as new, and de- 45 sired to be secured by Letters Patent, is—

1. In fireproof floor and ceiling constructions the combination of I-beams or girders, sectional building material, curved metallic bars placed alternately in reverse position in 50 the transverse joints of said material and a suitable cement for said material and bars, substantially as and for the purpose described.

2. In fireproof flooring and ceiling construction the combination with I-beams of continuous building material, curved metallic bars embedded alternately, in reverse position, at suitable distance apart in said material, substantially in the manner as and for the pur- 55 pose set forth.

In witness whereof I have hereunto set my hand in presence of two subscribing witnesses.

ALFRED P. ELTEN,
Administrator of the estate of Hermann Christian Wilhelm Weyhe, deceased.
